UNITED STATES PATENT OFFICE.

CARL G. RAY, OF RACINE, WISCONSIN.

FLEXIBLE FILING CABINET.

1,401,188.

Specification of Letters Patent. Patented Dec. 27, 1921.

Application filed April 26, 1921. Serial No. 464,662.

To all whom it may concern:

Be it known that I, CARL G. RAY, a citizen of the United States, and resident of Racine, in the county of Racine and State of Wisconsin, have invented certain new and useful Improvements in Flexible Filing Cabinets, and I do hereby declare that the following is a full, clear, and exact description thereof.

10 My invention refers to filing cabinets, and it has for its primary object to provide a flexible filing cabinet, wherein the partition walls forming pockets for articles to be filed are capable of automatic expansion and contraction with relation to each other to compensate for the thickness of articles filed therein. Thus the problem I have solved is the provision of means for automatically varying the size of the filing pockets, so as 15 to materially increase the capacity of a cabinet, bearing in mind that in filing articles, that the volume of such articles in some pockets greatly exceeds that of another. Hence, where the pockets are 20 of a fixed maximum capacity, it follows that a great deal of space is lost, due to the fact that articles of minimum volume must be inserted in the maximum pockets.

Another object of my invention is to provide a series of rigid, independently movable partitions, forming therebetween compensating pockets capable of varying in proportion to the thickness of articles filed therein.

35 To provide means for yieldingly pressing the series of partitions together, whereby the pockets are automatically adjusted in proportion to the volume of articles filed.

To provide for simultaneously shifting 40 the series of partitions in opposition to pressure, together with means for selectively locking any one of the partitions, whereby the pressure means will exert force to shift the associated partition, to thereby expand 45 the pocket associated with the lock partition for clearance, thus accomplishing a clearance space whereby access may be had to the articles filed in this particular pocket, in order that they may be removed or added to.

50 With the above and other minor objects in view, the invention consists in certain peculiarities of construction and combination of parts, as are hereinafter set forth with reference to the accompanying illustrations and subsequently claimed.

In the drawings:

Figure 1 represents a sectional elevation of a cabinet embodying the features of my invention, the length of the cabinet being contracted for convenience in illustration, 60 the section being indicated by line 1-1 of Fig. 2.

Fig. 2 is a cross-sectional plan view of the cabinet, with certain parts broken away to more clearly illustrate certain features, the 65 section being indicated by line 2-2 of Fig. 1, and

Fig. 3 is a contracted longitudinal sectional view of the cabinet, as indicated by line 3-3 of Fig. 1, the same showing the 70 cabinet parts with the partitions removed.

Referring by characters to the drawings, 1 represents the rear wall and 2-2 the side walls of a standard cabinet, provided with a hinged door 3 at its front for access thereto, the side walls below the door being connected by an apron 4, which, in conjunction with said side walls and rear wall, forms a well at the bottom of the cabinet for reciprocative movement of a tray composed of 80 top and bottom heads 5-6 respectively, which heads are connected by side panels 7-7 and a rear panel 8, the side panels being of slightly less width than the depth of the tray, whereby a clearance space is 85 formed for longitudinally disposed companion sets of rack bars 9-9-9'-9', which rack bars are secured to the side walls of the cabinet and are formed with upwardly extended saw teeth 10, as best shown 90 in Fig. 1. Obviously, these rack bars may be modified within the knowledge of skilled mechanics.

The front edge of the bottom head has 95 secured thereto an apron board 6', whereby the gap, incidental to movement of the tray in a vertical direction, is closed with respect to the front of the cabinet. Thus, it will be seen that the tray is in telescopic union with the cabinet, and is held against 100 lateral movement by the cabinet walls in one direction, and in the other direction by the bars 9-9', the edges of which serve as guides in connection with the abutting edges of the tray panels 7-7. The tray, in 105 this exemplification of my invention, is gravity controlled and is normally suspended at its lowermost position by a strap 11, which is secured to the top head 5 of the tray and to a spindle 12, which spindle is 110

journaled in suitable bearings formed therefor in the side walls of the cabinet. The spindle projects beyond one wall of the cabinet and terminates with a hand 5 crank 13.

Loosely and independently fitted within the tray is a series of rigid rectangular partitions 14. The partitions, as shown, are formed from metallic plates spaced apart 10 whereby a stiff hollow unit is developed. Reciprocatively mounted between the walls of each partition are companion pairs of locking plungers 15—15—15'—15', the noses of which are tapered to correspond 15 with the tooth surfaces of the rack bars 9—9' with which they engage. The reciprocative locking plungers are guided by blocks 16 at their inner ends, and by the walls of the partition about an opening 20 through which the nose portions of said plungers project when functioning.

The companion plungers are urged into engagement with the rack bars by springs 17—18, which springs in this instance are 25 formed in one piece and are coiled about anchor pins 19—20. From the anchor pins, the spring units take the form of a double wedge X that inclines in both directions from a central loop, and this double wedge 30 of the spring is controlled by a cam head 21 having wedge shaped flanges 22, which are adapted to engage the wedged faces X of the spring members. The cam is reciprocatively guided in a push rod 23, which rod 35 is secured to one of the walls of the partition, and movement is imparted thereto by the push rod 23, which push rod extends out through the front wall of the partition and terminates with a button.

40 Hence, it will be seen that when the push rod is drawn outwardly, as shown in Fig. 2, the spring elements 17—17—18—18 are permitted to function, whereby the plungers are held in yielding locked engagement with 45 their associated rack bars 9—9'. When it is desired to unlock the partition from the rack bars, the push rod 23 is moved inwardly by pressure of the operator, whereby the cam 21 will exert a wedging force upon the 50 central coils of the spring members to thus cause said members to rock upon their pivots 19 and 20, whereby they serve the purpose of levers to simultaneously retract the two sets of locking plungers from engagement 55 with the teeth of the rack bars.

The exemplification of my invention, as shown, is particularly arranged for use in connection with alphabetically arranging phonograph records, sheet music, general office filing, etc., whereby they can be quickly removed and replaced in a cabinet of minimum size. Obviously, the flexible cabinet may be used for storing any type of records or articles. In practice, it is desirable 60 to label each partition with an index,

and in connection with these indices a record sheet can be used, whereby the devices in the various pockets can be selected, but, of course, the indices arrangement forms no part of my invention except in so far that 70 it is a convenient method for locating and recording the articles stored in the cabinet.

While I have shown only three partitions in the cabinet to illustrate the principle of my invention, obviously the cabinet can be 75 supplied with a sufficient number to fill it when they are separated to produce the maximum pocket space. As shown in Fig. 1, for example, there are three partitions, A, B and C. Normally, the partitions are 80 snugly nested together, and when in use, they are spaced apart the thickness of the pile of records y contained therebetween.

Should it be desired to have access to the pile of records below the partition B, for 85 example, the operator will rotate the crank handle 13 and the tray will be raised a predetermined fixed distance by winding up the strap 11, upon the spindle 12. After this lifting of the gravity controlled tray is effected, the operator withdraws or pulls out the push rod 23 in connection with partition B, whereby its associated locking plunger will enter the racks simultaneously. The operator thereafter releases the crank 13 and 90 permits the tray to drop to its normal position, leaving the tray B and all trays thereabove locked in suspension. Thus the associated pocket of tray B containing the records y will be materially widened, for the 95 reason that all of the trays therebelow will travel downward by gravity to the limit of movement of said tray. This action leaves a clearance space at the top of the records to which access is desired, whereby the operator can readily remove such records as he may require, and when it is desired to return the records, the pocket, which is of the greatest width due to the locking action, is 100 in position to receive such records. 105

The operator then pushes the rod 23 inwardly, whereby the partition B is freed from the rack, and thus it, together with all partitions above, will drop down so as to form a compact mass. This action can be 115 imparted in connection with any pocket of the series, it being understood that the partitions are rigid, so as to sustain the suspended load, and when the partition is unlocked from engagement with the cabinet 120 walls, all of the mass above said partition will drop by gravity.

While I have shown a complete exemplification of my invention in all of its details, obviously I may vary the structural features, 125 as for example, any kind of locking mechanism can be used in connection with the rigid trays, and in some cases these trays may be locked by friction. In order to insure the dropping of the trays by gravity without 130

binding, I have, in this instance, shown a pair of wire stretches 24 which are secured to the back wall of the tray, and which stretches serve as metallic rails against which the rear edges of the trays may slide, thus making a metal contact whereby friction is avoided.

It will also be observed that the cabinet may be of any shape in cross-section, and 10 also that the partitioned walls may be varied as to shape indefinitely, without departing from the spirit of the invention.

It is also within the province of my invention to reverse the movement of the tray. 15 That is, said tray may be normally held at its uppermost position and depressed for obtaining the separation of the tray elements, and it should also be understood that as a substitute for the gravity arrangement 20 shown, I may employ a weight or springs, in which case the partitions would be arranged to slide horizontally under a yielding tension in place of sliding vertically, as shown.

It is further understood that I may vary 25 the structural features of the invention within the scope of the claims.

I claim:

1. A flexible filing device comprising a cabinet, a shiftable tray mounted therein, a 30 series of independently movable rigid partitions mounted in the tray, the partitions forming compensating pockets therebetween capable of varying in proportion to the thickness of the articles filed therein, means 35 for shifting the tray and series of partitions in either direction, and means for selectively

locking any one of the partitions to the cabinet, whereby the associated pocket thereof is expanded following movement of the tray.

2. A flexible filing device comprising a 40 cabinet, racks carried thereby, a vertically movable tray mounted in the cabinet, a series of rigid partitions normally supported by the tray and adapted to form pockets of varying sizes for articles inserted therebetween, the proportions of the pockets being controlled by gravity, means for lifting the tray, and means for locking any one of the partitions after the tray has been lifted, 45 whereby a clearance space is formed between the locked tray and its associated pocket for access to articles contained therein.

3. A flexible filing device comprising a cabinet, racks carried thereby, a vertically movable tray mounted in the cabinet, a series 50 of rigid partitions normally supported by the tray and adapted to form pockets of varying sizes for articles inserted therebetween, the proportions of the pockets being controlled by gravity, means for lifting the 55 tray, and manually controlled clutch means carried by each tray for locking the same after it has been lifted, whereby a clearance space is formed between the locked tray and its associated pocket for access to articles 60 contained therein.

In testimony that I claim the foregoing I have hereunto set my hand at Milwaukee, in the county of Milwaukee and State of Wisconsin.

CARL G. RAY.
